GARMENT RACK

Edwin H. Cordes, Bayside, N. Y.

Application January 25, 1949, Serial No. 72,638

3 Claims. (Cl. 211—176)

1

This invention relates to an adjustable clothes rack and more particularly to a clothes rack used for display purposes.

One object of the invention is to provide an adjustable garment-rack which is of simple construction and easy to adjust for supporting garments of various lengths.

Another object is the provision of a rack of improved appearance while at the same time providing convenient access to the garments supported on the rack for display and sales purposes in retail and other stores.

A further object is to provide a rack which is especially well adapted to be made of wood, although the rack may be made of other materials.

A yet further object is generally to provide a rack of improved construction and appearance.

The above and other objects, features and advantages of the invention will be more fully understood from the following description considered in connection with the accompanying illustrative drawings which show a preferred embodiment of the adjustable clothes rack of this invention.

In the drawings:

Fig. 1 is a perspective view of a clothes rack embodying the invention;

Fig. 2 is a side view of part of the rack;

Fig. 3 is a view similar to Fig. 2 with portions shown in section;

Fig. 4 is a side view of part of the cross-bar at the point where the card holder is attached;

Fig. 5 is a sectional view along line 5—5 of Fig. 4;

Fig. 6 is a sectional view along line 6—6 of Fig. 3;

Fig. 7 is a fragmentary view, on a larger scale, of the upright of the rack with a portion thereof shown in section;

Fig. 8 is a side view, partly in section, of a holding element provided in the rack;

Fig. 9 is a sectional view on the line 9—9 of Fig. 1.

In the drawings, the clothes rack 10 comprises four uprights 11 joined in pairs by spacing and connecting members 17 at the opposite ends of the rack. Each pair of uprights 11 is joined by a runner or longitudinal connecting member 19 secured to members 17. Each upright 11, of one pair, cooperates with a companion upright 11, of the other pair, to adjustably support a cross-bar 15, as will hereinafter be described. Garments (not shown here) may be suspended, side-by-side, from hangers hung from both cross-bars 15.

2

Uprights 11 are each preferably made of two initially separate sections 35, as indicated in Fig. 6. Said uprights are preferably made of wood. Each section 35 has a cut-out portion 36 which extends longitudinally partly down the inner surface thereof. The companion sections 35 are joined together by glue, or any other suitable means, to form a longitudinal channel, within the upper part of upright 11, preferably rectangular in cross-section, as in Fig. 6. It will be understood, however, that the interior channel may have other cross-sections, for example, circular, elliptical, etc., to accommodate the particular shape of the rod inserted therein. Layers of veneer 39 or other suitable coverings conceal the joints of sections 35. In the illustrated embodiment, rod 20, preferably rectangular in cross-section, is axially disposed within the channel 36 of upright 11 for slidable movement therein. 15 It will be understood that rod 20 may have a circular, elliptical, or other cross-section, to be insertable into a specifically shaped channel. Rod 20 is preferably formed of metal but may be formed of wood, plastic or any other substance 20 25 strong enough for the purpose intended herein. As shown in Fig. 9 the lower parts of uprights 11 are preferably unchanneled. Rod 20 is freely slidable within and projects out of upright 11. Said rod is provided with a plurality of spaced 20 transverse apertures 29, for the purpose to be 30 hereinafter described. Upright 11 is provided with transverse aperture 30 to cooperate with a selected aperture 29 in rod 20 in the vertically adjusted position thereof. A pin 13, having a grooved portion 14 and a ball or other suitably shaped head 16, is removably insertable into aperture 30 and through one of the apertures 29 in rod 20. Groove 14 is slightly wider than rod 20 whereby the rod sits in the groove, locking pin 13 in position, as in Fig. 7. Pin 13 is preferably formed of metal, but may be formed of wood, plastic or any other substance strong enough to hold rod 20 in position. The pin is threaded 40 at one end to receive head 16 shaped for easy grasping of the pin. Pin 13 is readily removable from upright 11 by slightly raising rod 20 to clear the sides of groove 14. As illustrated by the dotted lines at the top of Fig. 7, rod 20 is movable in upright 11 to align its different apertures 45 50 55 29 with aperture 30 for the insertion of pin 13 whereby the rod will project from the upright for a predetermined distance.

Upright 11 is preferably formed of upper part 33 and lower part 34 which are mutually angularly disposed to diverge from the center of the

upright. Due to the diverging disposition of the upper portion 33, the rod 20 travels obliquely when moved outwardly from upright 11. While the lower portions 34 have been illustrated as diverging to provide a wider mount for the rack, it will be understood that the lower portions 34 may be vertical and the upper portions 33 alone made to diverge from the vertical lower portion, or the upper parts may be vertical and the lower parts may be inclined, or said uprights may be vertical for their full lengths.

Uprights 11 are preferably provided with metal wear sleeves 12 at the entrance to the channels therein, respectively. Rod 20 has a turned portion 21 at the top thereof. Cross-bar 15, preferably a hollow metal tube, has inserted at each end thereof, a turned plug 24, preferably of metal. Plug 24 is provided with a transverse aperture into which is fitted the turned portion 21, through an opening in the underside of the cross-bar. Turned portion 21 is secured in plug 24 by a screw 25, or in any other suitable way. In this manner, each cross-bar 15 is supported at each end, by one rod 20 retained within one upright of each pair, as illustrated.

Connecting members 17 are preferably made of wood and are provided with integral lateral extensions or tongues 37, shown in dotted lines in Fig. 1. Each extension 37 is fitted and glued into a companion groove provided in the center of upright 11. The extensions 37, when secured into the cooperating grooves in uprights 11, retain both uprights of each pair in proper spaced relationship, as illustrated. It will be understood that other means may be used to join the uprights and connecting spacers 17, for example, dowels may be carried by the spacer and be forced into cooperating openings in the uprights. Runner 19, preferably made of wood, serves to retain the spacers 17 for the uprights 11 in their proper spaced relation. Runner 19 and spacers 17 are joined together by angles 22, as shown in Fig. 1. Screws 31, or any other suitable means, are used to fasten the angles in the corners formed when runner 19 is placed substantially perpendicularly to the inner surfaces of spacers 17. Dowels 32, carried by each end of runner 19, are fitted into cooperating apertures in the center of spacers 17. It will be understood that the projecting portions 37 on spacers 17 extend into uprights 11 below the lower ends of channels 36. It will be further understood that spacers 17 and runner 19, although preferably made of wood, may be fabricated from metal, plastic or any other substance suitable for the purpose of the present invention.

The manner of using the rack is considered obvious from the above description. It will be noted that either cross-bar 15 is vertically adjustable independently of the other so that longer garments or other articles may be suspended by their hangers from one suitably adjusted cross-bar while shorter garments may be suspended by their hangers from the other suitably adjusted cross-bar. For example, as shown in Fig. 1 the cross-bar 15 at the right is at a higher position than the other cross-bar. The inclination of the upper parts 33 of the uprights is preferably such that the garments supported by the cross-bars are not crowded against runner 19, although cross connecting members 17 may be comparatively short. The lower ends of uprights 11 may be provided with casters or slide domes (not shown), as will be readily understood.

It will be noted that the rack 10 may be shipped

to its destination in disassembled or knock-down form and thereafter easily assembled. In this connection it will be noted that runner 19 is removably secured to members 17 by the screw 5 fastened angle members 22, and that bars 15 are releasably secured to rods 20 by end members 24 and screws 25. Accordingly, the rack may be shipped with runner 19 and bars 15 disconnected from the other parts of the rack, in a shipping 10 container of comparatively small size, or the rack may be disassembled for storage purposes.

Card holders 23 may be provided for the garments carried by the hangers (not shown) suspended from cross-bars 15, for purposes of display or otherwise, said card holders may be affixed to the center or other suitable part of each cross-bar 15. Each card holder 23 is provided with a rod 38 which is affixed to and passes through a saddle 26. Saddle 26 is preferably 20 curved to conform to the portion of cross-bar 15 upon which it rests, as shown in Fig. 5. Rod 38 extends through aligned openings in the top and bottom of cross-bar 15 and through a washer 27 on the underside of cross-bar 15. The end 25 of rod 38 projecting from the underside of cross-bar 15 is threaded to receive a wing nut 28 which is screwed onto rod 38 to retain card holder 23 in position.

Thus, it is seen that the clothes rack described 30 above is well adapted to accomplish the objects of the invention. Although primarily intended as a display rack, it will be understood that the rack may be equally well used in storerooms, checkrooms and homes. Various changes may 35 be made without departing from the underlying idea of the invention within the scope of the appended claims.

Having thus described my invention, what I claim and desire to secure by Letters Patent is:

1. An adjustable rack comprising a first pair of upright members, each of said members having mutually diverging portions, said members of the pair being spaced in mutual diverging relationship, a second pair of upright members spaced from said first pair, each of the upright members of said second pair having similar mutually diverging portions and the members of the second pair being spaced in mutual diverging relationship, each of said upright members having a longitudinal channel in the upper portion thereof and having a rod axially adjustable in said channel, a pair of laterally spaced cross-bars, extending longitudinally between said first and second pairs of upright members, each of said bars being supported by a rod of one of said 45 pairs of upright members and by a rod of said other pair of upright members, and adjustable thereby in mutually intersecting planes.

2. An adjustable rack comprising a first pair 60 of upright members, each of said members having mutually diverging portions, said members of the pair being spaced in mutual diverging relationship, a second pair of upright members spaced from said first pair, each of the upright members of said second pair having similar mutually diverging portions and the members of the second pair being spaced in mutual diverging relationship, transverse members interposed and extending between the companion upright members 65 of each pair and connecting the members of each pair in fixed relation and disposed in position intermediate the diverging portions of the upright members of the pair to which said transverse members are connected, respectively, a longitudinal member extending between said 70 75

transverse members and rigidly connecting them to each other, and longitudinal garment supporting bars extending between correspondingly positioned upright members of different pairs and supported thereby in position at the top of the rack, said bars being disposed laterally outwardly of the plane of said longitudinal connecting member.

3. An adjustable rack comprising a first pair of upright members, each of said members having mutually diverging portions, said members of the pair being spaced in mutual diverging relationship, a second pair of upright members spaced from said first pair, each of the upright members of said second pair having similar mutually diverging portions and the members of the second pair being spaced in mutual diverging relationship, transverse members interposed and extending between the companion upright members of each pair and connecting the members of each pair in fixed relation and disposed in position intermediate the diverging portions of the upright members of the pair to which said transverse members are connected, respectively, a longitudinal member extending between said transverse members and rigidly connecting them to each other, each of said upright members having a longitudinal channel in the upper portion

10

5

thereof and having a rod axially adjustable in said channel, a pair of laterally spaced cross-bars, extending longitudinally between said first and second pairs of upright members, each of said bars being supported by a rod of one of said pairs of upright members and by a rod of said other pair of upright members, and adjustable thereby in mutually intersecting planes.
